(57) **CLAIM**

The ornamental design for a brimless cap, as shown and described.

DESCRIPTION

FIG. 1 is a perspective view of the brimless cap.

FIG. 2 is a front elevational view of the brimless cap.

FIG. 3 is a rear elevational view of the brimless cap.

FIG. 4 is a left side elevational view of the brimless cap.

FIG. 5 is a right side elevational view of the brimless cap.

FIG. 6 is a top plan view of the brimless cap.

FIG. 7 is a bottom plan view of the brimless cap.

FIG. 8 is a perspective view of the brimless cap in a folded and zipped configuration.

FIG. 9 is a front elevational view of the brimless cap in a folded and zipped configuration.

FIG. 10 is a rear elevational view of the brimless cap in a folded and zipped configuration.

FIG. 11 is a left side elevational view of the brimless cap in a folded and zipped configuration.

FIG. 12 is a right side elevational view of the brimless cap in a folded and zipped configuration.

FIG. 13 is a top plan view of the brimless cap in a folded and zipped configuration.

FIG. 14 is a bottom plan view of the brimless cap in a folded and zipped configuration; and,

FIG. 15 is a perspective view of the brimless cap in an additionally folded configuration.

The broken lines on claimed surfaces depict stitching and form no part of the claim.

1 Claim, 13 Drawing Sheets
